UNITED STATES PATENT OFFICE.

ERNEST WALTER BRUDENELL GILL, OF OXFORD, ENGLAND, ASSIGNOR TO RADIO CORPORATION OF AMERICA, OF NEW YORK, N. Y., A CORPORATION OF DELAWARE.

WIRELESS-TELEGRAPH RECEIVER.

1,371,757.

Specification of Letters Patent. Patented Mar. 15, 1921.

Application filed October 7, 1920. Serial No. 415,408.

To all whom it may concern:

Be it known that I, ERNEST WALTER BRUDENELL GILL, a subject of the King of Great Britain, residing at Merton College, Oxford, England, have invented certain new and useful Improvements in Wireless-Telegraph Receivers, of which the following is a specification.

This invention relates to wireless telegraph receivers of the type in which the signals to be received act upon the grid of a valve, the anode of which is connected directly to the grid of a second valve, while the variations in the current in the anode circuit of this second valve act upon a current indicator such as a telephone receiver.

According to this invention I provide means for adjusting the voltage of the first grid so that the current in the anode circuit of the second valve may decrease as the voltage of the first grid increases, and increases as the voltage of the first grid decreases, or in other words the anode current of the second valve is varied inversely with the potential of the grid of the first valve through a portion of a cycle.

In accordance with this invention the voltage of the first grid may also be adjusted with respect to the signal strength so that the variations of the current of the anode of the second valve occur between the same limiting values of maxima and minima for all signals above a predetermined signal strength.

Preferably also the negative side of a small battery is connected to the first grid.

My invention is illustrated by the accompanying drawing.

Figure 1 is a diagrammatic view of a receiving system in accordance with the invention.

Fig. 2 is a curve showing the relation of the anode current in the second valve to the grid voltage of the first valve.

Fig. 3 shows a number of anode current-grid voltage curves with different values of filament current.

Fig. 4 shows a number of anode current-grid voltage curves with different values of anode voltage.

In Fig. 1 F f are the filaments, G g the grids and A a the anodes of two valves, the filaments being connected in parallel to a battery B through a resistance R. The

anode A and the grid g are connected together, but otherwise they are insulated. The voltage of the grid G can be adjusted by means of a potentiometer P, a small battery C being inserted between the potentiometer and the grid and having its negative side connected to the latter. D is a tuned oscillatory circuit loosely coupled to an aerial E. The anode a is connected through a telephone T and a battery V to the filament circuit.

The valves should be fairly hard.

Such an arrangement gives a characteristic of the form shown in Fig. 2, the abscissæ being volts between the filament F and grid G, and the ordinates being the values of the current in the circuit of the anode a. It will be seen that as the grid G has its potential increased (positively) with regard to the filament F, the anode current of the second valve is approximately constant from K to L; from L to M it decreases, and then becomes approximately constant again from M onward. From L to M the combination has a negative resistance, i. e. increase of applied volts results in a diminution of the current; and the arrangement has two rectifying points L and M.

The curves in Fig. 3 show the effect of varying the filament currents, keeping the plate voltage fixed, while those in Fig. 4 give the result of keeping the filament current constant and varying the plate voltage. In both these figures the abscissæ are grid volts and the ordinates anode currents in microamperes. In Fig. 3 the difference in potential between the anode a and the filament f is constant and equal to 40 volts, while the filament current in amperes is shown by the figures to the right of each curve, the filament currents in the two valves being approximately equal. Similar results can be obtained by varying the filament current of the first valve only, keeping the second constant, the filament current of the first valve being the determining factor. In Fig. 4 the heating current is .53 amperes for all three curves, while the anode volts are shown by the figures to the right of each curve.

Fig. 4 shows that there is only one result from increasing the plate voltage of the second valve, and that is to increase the cur-

rent drop; the place on the potentiometer where the drop begins and ends being about the same for all plate volts; increase in plate volts therefore increases the steepness 5 of the curve.

Fig. 3 on the other hand shows that variation of the filament current has no appreciable effect on the steepness but determines the extent of the drop. Hence by suitably 10 adjusting the plate volts and the filament current any desired curve in reason can be obtained, for instance, a small steep drop can be obtained by using a large plate voltage and a low filament current.

15 Signals will be heard in the telephone when the potentiometer is adjusted to give either L or M of Fig. 2. The signals at L are always better than those at M, this being due to the fact that at M damping is 20 produced by the current flowing into the first grid.

There are two main uses to which the device can be put for reception:

(1) Limitation.
25 (2) Discrimination between different types of signals.

With regard to (1), the maximum rectification depends on the drop from L to M; if therefore this drop is made small, which 30 can be done as explained above, all signals over a certain strength will give sounds of equal strength in the telephone.

With regard to (2), between the two rectifying points L and M signals go to a minimum, and it has been found experimentally that the positions of these minima differ for different types of sending gear. Thus the minimum for a Telefunken is not the same as for a British navy spark, and it is possible 35 if their strengths are about the same to hear the Telefunken only on one adjustment, and the navy only on another adjustment. Disturbances due to certain types of "atmospherics" can also be reduced relatively to the signals it is required to receive.

Having now particularly described and ascertained the nature of my said invention and in what manner the same is to be performed, I declare that what I claim is:

50 1. In a wireless telegraph receiver the combination of two valves each having a grid, an anode and a cathode, the cathodes being at substantially the same potential, means for causing incoming signals to affect the grid of the first valve, a low resistance connection between the anode of the first valve and the grid of the second valve whereby these are at the same potential and an indicator actuated by variations in the 55 anode current of the second valve.

2. In a wireless telegraph receiver a combination of two valves each having a grid, an anode and a cathode, the cathodes being at substantially the same potential, a battery 60 having the negative side connected to

the grid of the first valve, means for causing incoming signals to affect said grid, a low resistance connection between the anode of the first valve and the grid of the second valve whereby these are at the same potential 70 and a detector actuated by variations in the anode current of the second valve.

3. In a wireless telegraph receiver, the combination of two valves, each having a grid, an anode and a cathode, the cathodes 75 being at substantially the same potential, a battery having the negative side connected to the grid of the first valve, means for causing incoming signals to affect said grid, a low resistance connection between the anode of 80 the first valve and the grid of the second valve whereby these are at the same potential, a battery connected between the anode and the cathode of the second valve and an indicator actuated by variations in the anode 85 current of the second valve.

4. In a wireless telegraph receiver the combination of two valves each having a grid, an anode and a cathode, the cathodes being at substantially the same potential, 90 the anode of the first valve being disposed to accumulate a charge from its cathode, means for causing incoming signals to affect the grid of the first valve whereby the charge on the anode is varied, a low resistance connection between the anode of the first valve and the grid of the second valve 95 whereby these are at the same potential and an indicator actuated by variations in the anode current of the second valve.

100 5. In a wireless telegraph receiver the combination of two valves each having a grid, an anode and a cathode, the cathodes being at substantially the same potential, the anode of the first valve being disposed to 105 accumulate a charge from its cathode, a battery having the negative side connected to the grid of the first valve, means for causing incoming signals to affect said grid whereby the charge on the anode is varied, a low resistance connection between the anode of the first valve and the grid of the second valve 110 whereby these are at the same potential and a detector actuated by the variations in the anode current of the second valve.

115 6. In a wireless telegraph receiver the combination of two valves each having a grid, an anode and a cathode, the cathodes being at substantially the same potential, 120 the anode of the first valve being disposed to accumulate a charge from its cathode, a battery having the negative side connected to the grid of the first valve, means for causing incoming signals to affect said grid whereby 125 the charge on the anode is varied, a low resistance connection between the anode of the first valve and the grid of the second valve whereby these are at the same potential, a battery connected between the anode 130

and the cathode of the second valve and an indicator actuated by variations in the anode current of the second valve.

7. In wireless telegraph receivers the combination of two valves each having a grid, an anode and a cathode, the anode of the first valve being disposed to accumulate the charge from its cathode, a battery connected to the grid of the first valve, means for causing incoming signals to affect said grid whereby the charge on the anode is varied, a connection between the anode of the first valve and the grid of the second valve, and an indicator actuated by variations in the anode current of the second valve.

8. In a wireless telegraph receiver the combination of two valves each having a cathode, an anode and a grid, the anode of the first valve being disposed to accumulate a charge from its cathode, a battery having the negative side connected to the grid of the first valve, means for causing incoming signals to affect said grid whereby the charge on the anode is varied, a connection between the anode of the first valve and the grid of the second valve, a battery connected between the anode and cathode of the second valve and an indicator actuated by variations in the anode current of the second valve.

9. In a wireless telegraph receiver the combination of two valves each having a cathode, an anode and a grid, the anode of the first valve being disposed to accumulate a charge from its cathode, a battery having the negative side connected to the grid of the first valve, means for causing incoming signals to affect said grid whereby the charge on the anode is varied, a connection between the anode of the first valve and the grid of the second valve, means for varying the electron emission of the cathodes and an indicator actuated by variations in the anode current of the second valve, the voltage applied to the grid being adjusted so that the anode current of the second valve varies inversely with the potential of the grid of the first valve and the electron emission of the valves being adjusted so that said anode cur-

rent varies between the same limiting values 50 for all effects above a pre-determined signal strength.

10. In wireless telegraph receivers the combination of two valves each having a grid, an anode and a cathode, the anode of the first valve being disposed to receive a charge from its cathode, a battery connected to the grid of the first valve, means for causing incoming signals to affect said grid whereby the charge of the anode is varied, a connection between the anode of the first valve and the grid of the second valve, an indicator actuated by variations in the anode current of the second valve, the voltage applied to the grid of the first valve being adjusted so that the anode current of the second valve varies inversely with the potential of the grid of the first valve when said grid is subjected to incoming signals.

11. In a wireless telegraph receiver the combination of two valves each having a cathode, an anode and a grid, the anode of the first valve being disposed to receive a charge from its cathode, a battery having the negative side connected to the grid of the first valve, means for causing incoming signals to affect said grid whereby the charge on the anode is varied, a connection between the anode of the first valve and the grid of the second valve, a battery connected between the anode and cathode of the second valve and an indicator actuated by variations in the anode current of the second valve, the voltage applied to said grid being adjusted so that the anode current of the second valve varies inversely with the potential of the grid of the first valve when the grid is subjected to signals and the voltage applied to the anode of the second valve being adjusted so that said anode current varies between the same limiting values for all the effects above a predetermined signal strength.

In testimony whereof I have hereunto affixed my signature this twenty first day of September 1920.

ERNEST WALTER BRUDENELL GILL.
